UNITED STATES PATENT OFFICE

HENRY A. DREFFEIN, OF CHICAGO, ILLINOIS

KILN AND BURNER APPARATUS

Application filed October 4, 1928. Serial No. 310,389.

This invention relates to kilns and burner apparatus and has among its objects to provide apparatus which will effect the efficient burning of raw producer gas for kiln heating; to provide apparatus of the character indicated, including master control for the air and master control for the gas, with or without individual shut-off means for the separate air and gas supplies to the individual burners; to provide a new burner for burning gas, particularly raw producer gas, to decrease or eliminate the deposit of condensable hydrocarbons and tarry substances; to provide apparatus for the obtaining of a delayed combustion of the gas and air; to provide apparatus for the burning of raw producer gas in which interchangeable fixed orifice members are utilized with either or both the separate gas and air supply means for each burner whereby proper orifices having been provided further regulation is not required; to provide means for the maintenance of the gas orifices in clean condition without interfering with the operation of the apparatus and from the exterior of such apparatus; and in general to provide a new and improved method and apparatus to practice that method for the efficient burning and use of gas.

These and other objects will be apparent and more fully set forth in the following specification and shown in the accompanying drawings, in which:

Fig. 1 is a vertical, irregular section through a kiln, illustrating an embodiment of my invention;

Fig. 2 is a side elevation of a portion of the gas and air delivery equipment;

Fig. 3 is a vertical section along the line 3-3 of Fig. 4;

Fig. 4 is a vertical section along the line 4-4 of Fig. 3;

Fig. 5 is a horizontal section along the line 5-5 of Fig. 4;

Fig. 6 is a horizontal section along the line 6-6 of Fig. 2, showing one of the air orifice discs.

Fig. 7 is a vertical section along the lines 7-7 of Fig. 1.

Like numerals refer to like elements

throughout the drawings, in which 10 indicates generally a kiln having tracks 11 in the bottom thereof for the conveyance of the cars on which are carried the articles to be heated. Longitudinally of the kiln at each side thereof are muffle ducts 12 of suitable refractory or other material.

At suitable intervals along the length of and delivery into such muffle, ducts are provided open ended hoods 13 having outlet ports 12a which communicate with gas supply ducts 14. At the entrance end of the gas ducts 14 are provided refractory nozzle members 16, each with tapered bore and mounted in a surrounding metal shell 17, as illustrated in Fig. 4, for example. A box 18 is in communication with each of the nozzles 16 at the inlet end thereof through a port 18a. To properly control or determine the supply of gas for proper combustion, a disc 20 is provided for each of the ports 18a, which is detachably secured to the inner wall of the box 18 by means of bolts or studs 21, for example. Each of these discs is provided with an orifice 20a which determines the size of aperture through which the gas must flow to the nozzle member 16. Interchangeable discs are provided with different sized orifices so that it is a simple matter to supply the proper size of orifice required for the proper operation of any burner unit.

In the wall of the box 18 opposite the port 20a is provided a second aperture 18b which is normally closed by a cap 23 having small central apertures to accommodate a cleaning rod 25, which projects therethrough and through the orifice 20a and the disc 20. The rod 25 is provided with a shoulder 25a and a handle 26, located exteriorly of the cap 23 and box 18. The shoulder 25a snugly fits the aperture in cap 23, but the small central aperture is slightly larger than the diameter of the rod 25. As tar or other substance is deposited upon the edge of the orifice 20a from time to time the rod 25 may be partially withdrawn until shoulder 25a is moved from its seat, when the rod, due to its loose fit, may be rotated or oscillated in contact with the edge of the orifice 20a to scrape or rub off the accumulated deposit thereon. Due to the

exterior location of the handle 26 this cleaning operation may be readily effected during the operation of the burner without interference therewith. A plurality of additional 5 apertures 18c is located around the aperture 18b and these are normally covered by caps 27, which are detachably secured by bolts or the like in closed relation, as illustrated in Fig. 3. These ports may be used for observation, clean-outs, or other purposes, as may the central port 18b.

Looped around the kiln is a main gas supply pipe 29 to which gas is supplied through the main 29a, the latter being provided with 15 a main shut-off gate valve 29b or the like. In the form shown, manifolds 32 are provided, each supplying gas to a pair of burners and supplied with gas by the branch pipe 30 leading from the main supply pipe 29. 20 At the juncture of each branch 32 with a box 18, there is provided a valve seat 32a with which coacts a quick acting valve 33 to fully open or close communication between the branch 32 and the casing 18. In the form 25 illustrated each of these valves is provided with an upwardly projecting rod or stem communicating by a flexible connecting member 35 with a segment 36 to which it is secured. The segment is provided with attached arm 36a rotatably mounted in a bifurcated bracket 37. A connecting spring 38 is attached to the outer end of the arm 36a and is provided with a loop for engagement with the stud 39 projecting from the branch 30 pipe 32, the purpose of this construction being to permit quick movement of the handle 36 to fully open the valve 33, the spring connector 38 serving when connected to stud 39 to maintain the valve in open position. It 35 will be apparent that other suitable means may be substituted for the same purpose.

Also looped around the kiln 10, is an air supply pipe 39 fed by the main 39a having a shut-off valve 39b therein. From the main 45 air supply pipe 39 lead branch pipes 40 to each of the burners, each of these pipes 40 also being provided with a shut-off valve 40a of suitable construction. In each of the branch pipes 40 is provided an enlargement 50 such as a coupling or the like as indicated by numeral 40b (see Figs. 1 and 6) grooved to permit the sliding insertion or removal of a disc 40c, which is provided with an orifice 40d therein. These discs are interchangeable 55 and may be provided with different sized orifices to permit selection of the proper orifice for each air branch pipe 40 to properly regulate or determine the amount of air flowing therethrough for admixture and combustion 60 with the gas delivered to the same burner unit.

Leading from each air supply branch 40 is an elbow 41 communicating with the port 41a in the gas duct 14, this port being located adjacent the bottom of the duct. The elbow 41

is inclined with respect to the longitudinal axis of the duct 14 and is arranged to deliver air to such duct at one side thereof at an angle to its axis preferably less than 90° with respect to the direction of the flow of the gas therethrough. This arrangement of the port 70 41a and the elbow 41, is such as to cause the air to follow a helical path about the periphery of the duct 14, as will be apparent.

When the proper orifices have been determined after determination of the proper amounts of air and gas to be delivered to each burner unit, and after placement of the discs with such orifices therein, in the individual 75 gas and air supply lines, the apparatus is ready for operation. With the main or master valves 29b and 39b open and the separate gas and air control valves 33 and 40a also open, and after ignition of the gas mixtures in the burner units, the air flowing through the ports 41a will, to a large extent 80 at least, envelop and surround the gas being delivered into duct 14. Some combustion ensues at the zone of meeting between the air and gas, but the air and gas being, in a sense, stratified, combustion is only partial and is delayed during the passage of the air and gas through the duct 14 so that the gases of combustion are delivered at a high temperature 85 into the muffle ducts 12. In this manner a greater efficiency of heating is obtained than would be obtained were the air and gas commingled at the nozzle 16, for example, in conventional manner and combustion completed 90 shortly after such mixture. Also, with only partial combustion in the duct 14 the heat to which the refractory is subjected is much less than would otherwise be the case, thus prolonging the life of the refractory and dispensing with a considerable heat loss during 95 flow through the duct 14.

While raw producer gas has been difficult, if not impossible, to handle heretofore in muffle type kilns due to the presence of condensable hydrocarbons or tarry substances, which deposit upon the walls of the ducts and gradually clog and restrict the ducts and seriously interfere with the operation of the apparatus, with my apparatus such condensables may deposit, in part at least, in the bottom of each box 18, a sump A being provided by the location of port 18a above bottom of the box 18. If this deposit, which is of a viscous or tarry nature, be not removed it will rise until it overflows into the nozzle member 16, hence it will flow down into the duct 14. The heat of the partial combustion taking place at the zone of contact between the air envelope and the enveloped gas, is sufficient 110 to volatilize and burn these tarry substances flowing down in the manner indicated, and any ash resulting from such combustion will be readily carried through into the muffle ducts where it may be removed from time to time without difficulty. Likewise, the envelope 115

lope of air and the zone of partial combustion will prevent the condensation of any condensable hydrocarbons in the gas flowing through the duct 14 and will maintain them in volatile or suspended condition

5 tain them in volatile or suspended condition until they burn, thus preventing the deposit of impeding material in the duct 14 and increasing the efficiency of the combustion.

10 It will thus be apparent that the method of stratifying the air and gas in the manner described serves two purposes: One, to dispose of any tarry substances flowing into the duct 14 from nozzle member 16, and the other, to

15 prevent, in a large part at least, the deposit of condensable or suspended hydrocarbon upon the wall of the duct 14.

It will also be apparent that, as stated above, the gas orifices 20a may be readily 20 maintained in clean condition without shutting down the operation of the corresponding burner unit, by manipulation of cleaning rods 25. Ports 18b and 18c also afford means of ready access to or inspection of the gas 25 orifices and nozzles, as well as the boxes 18.

It will be further apparent that having properly selected the orifices for the air and gas supply, the entire apparatus may be thrown into or out of operation by actuation 30 of the master gas and air valves alone, thus dispensing with separate control and regulation from time to time of the individual air and gas supplies and precluding tampering with them by the operator or others. At the 35 same time, where it is unnecessary to operate any one or more of the burner units, means is provided to quickly shut off the air and gas supply to such unit or units without requiring a readjustment or redetermination of the 40 proper amount of air and gas supply required when such units are again put into operation, this being due again to the provision of the orifice discs.

This system or apparatus permits the use 45 of raw producer gas in muffle kilns where it has hitherto been impractical due to the clogging of the ducts, nozzles and the like, with the condensable hydrocarbons and tarry substances, and due to the difficulty of obtaining 50 accurate regulation of the air and gas supply, particularly the latter, to each burner.

It will be apparent that my process and apparatus are susceptible of modification and variation from the form and method described in the above specification and illustrated in the accompanying drawings, and I do not wish to be restricted to such showing and description except as defined in the 55 appended claims interpreted with the proper range of equivalents.

What I claim is:

1. In apparatus of the class described, a duct, means to supply gas thereto, and an air duct communicating with said first named duct adjacent the wall thereof, said air duct

being constructed and arranged to deliver air into said first named duct around the periphery thereof and around the gas flowing therethrough at an angle to the direction of flow of said gas.

2. In apparatus of the class described, a duct, means to supply gas thereto, and an air duct communicating with said first named duct adjacent the wall thereof, said air duct being constructed and arranged to deliver air into said first named duct around the inner periphery thereof and around the gas flowing therethrough at an angle of less than 70 90° to the direction of flow of said gas.

3. In apparatus of the class described, a duct, means to supply gas thereto including a casing, said casing being provided with a port, a disc removably attached to said casing and provided with an orifice in alignment with said port, and means to clean said orifice 80 85 operable from outside of said casing.

4. In apparatus of the class described, a duct, means to supply gas thereto including a casing, said casing being provided with a port and a disc provided with an orifice in alignment with said port, and means to clean 90 95 said orifice from the outside of said casing, said means comprising a rod projecting through said orifice and having a portion projecting externally of said casing, said rod being movable about the periphery of said orifice to clean the same.

5. Apparatus of the class described having a plurality of ducts, means to separately supply gas to each of said ducts, said means including a casing having a port, a common supply member for said casings, and a valve for each of said casings movable to and from full open and full closed positions, and means to separately supply air to each of said ducts, each of said casings being provided with interchangeable orificed discs to determine the volume of gas delivered to said ducts.

6. Apparatus of the class described, having a duct, a nozzle member communicating therewith, a casing adjacent said nozzle and provided with a port communicating therewith, said port being located above the bottom of said casing to form a sump for the collection of deposited material from the gas flowing through said casing, said nozzle having its inner bore increasing in diameter from said casing toward said duct.

7. Apparatus for burning raw producer gas, comprising a plurality of gas supply pipes and a plurality of air supply pipes, orificed discs associated with said gas and air pipes to determine the flow of gas and air therethrough, a main gas supply means communicating with each of said gas supply pipes, a main air supply means communicating with each of said air supply means, a master shut-off valve for said main gas supply means and a master shut-off valve for said main air supply means, each of said gas and air supply

pipes being provided with a separate shut-off valve.

8. In apparatus of the class described, a duct, means to supply gas thereto and means to supply air at the inner periphery of said duct in such wise as to envelop said gas.

9. In apparatus of the class described, a duct, means to supply gas thereto and axially thereof and means to supply air tangentially of the inner periphery of said duct to envelop said gas.

10. In apparatus of the class described, a duct, means to supply gas thereto, means to supply air tangentially of the inner periphery of said duct around the gas flowing therethrough and at an angle less than 90° to the axis of said duct.

11. In apparatus of the class described in combination, a nozzle, a duct forming a continuation thereof, means to supply gas through said nozzle into said duct axially thereof and means to supply air around the inner periphery of said duct to envelop said gas.

12. In testimony whereof, I have signed my name to this specification.

HENRY A. DREFFEIN.
